ELECTROMAGNETIC RELAY WITH MULTIPLE INVERSE TIME RELATIONSHIPS

John H. Michael, West Allis, Wis., assignor to Allis-Chalmers Manufacturing Company, Milwaukee, Wis.

Application January 25, 1951, Serial No. 207,746

5 Claims. (Cl. 175—372)

1

This invention relates to improvements in automatic circuit protective devices and more particularly to a new and improved delayed action overcurrent electromagnetic relay.

The usual type of electromagnetic relay has a characteristic fast action which is not adapted to certain circuit arrangements, such as are involved in switchgear circuit breaker practice. These applications require a relay with a time delayed action. The period of time during which electric equipment can be subjected to abnormal conditions, such as high currents or short circuit currents, is ordinarily variable depending upon the character or intensity of such abnormal conditions. In some cases it is desirable to permit the electric system to remain intact for a period of time that varies with the value of an abnormal condition. At high values of overload currents or short circuit currents, it is desirable that the circuit be interrupted after a time interval which is comparatively small but which, nevertheless, insures freedom from interruption due to momentary disturbances.

Power distribution systems are frequently protected by a number of serially connected circuit breakers which operate in a predetermined sequence. Each serially connected breaker is adjusted to trip at a different predetermined interval of time, thereby sequentially isolating segments of the electric circuit in accordance with the location of the disturbance, the length of time the disturbance continues or the character of the disturbance. Heretofore, time delay relays have been used to sequentially trip serially connected circuit breakers but these relays have not been capable of accurate settings for such short time intervals as are desirable for clearing circuit faults with a minimum of burning of connections and connected apparatus.

In accordance with the invention claimed, a new and improved delayed action overcurrent electromagnetic relay is provided for circuit breaker operation which has a given current time characteristic for currents up to a predetermined value and different current time characteristics for currents above that predetermined value.

In the preferred embodiments of the invention the magnetic relay embodies an armature which actuates a switch operating rod. The rod is retarded by a pair of suction disks from moving into switch actuating position in a time varying inversely of the force exerted on the rod. This force varies with the current traversing the winding of the relay as long as the magnetic circuit of the relay remains unsaturated. For currents

2

below a predetermined value the armature remains in the position shown adjacent the relay core structure to provide an air gap of a predetermined value, and for currents above a certain value the armature is actuated to provide one or more positions which define air gaps of smaller values.

In order to accurately calibrate the electromagnetic relays so as to trip a plurality of serially connected circuit breakers, the relay is provided with means for varying the tension on the springs arranged between the armature and a flange provided on the switch actuating rod without varying the size of the original air gap.

15 It is, therefore, one object of the present invention to provide a new and improved delayed action overcurrent electromagnetic relay in which the relay has a given current time characteristic for overload currents up to a predetermined value and different current time characteristics for currents above that predetermined value.

Another object of this invention is to provide a new and improved delayed action relay which is adjustable for operation at predetermined current values with predetermined periods of time delay.

30 A further object of this invention is to provide a new and improved delayed action magnetic relay with multiple inverse time relationships which provide for adjustments of the point of changeover from one relationship to the other.

Objects and advantages other than those set forth will be apparent from the following description when read in connection with the accompanying drawing, in which:

35 Fig. 1 is a diagrammatic view of a circuit breaker and a delayed action overcurrent electromagnetic relay therefor embodying the present invention;

40 Fig. 2 is a view in axial cross section through a modified embodiment of the armature and controlling structure used therewith illustrated in Fig. 1;

45 Fig. 3 is a graph of the current time characteristics of the electromagnetic relay illustrated in Fig. 1 and a graph of a current time characteristic of a relay similar to the one illustrated in Fig. 1 but embodying the armature and controlling structure illustrated in Fig. 2.

50 Referring more particularly to the drawing by characters of reference, Fig. 1 illustrates an electric circuit 6 provided with a circuit interrupter or breaker 7 and a time delay overcurrent electromagnetic relay 8 for controlling its actuation at predetermined overloads. The relay comprises

a magnetizing winding 9 connected to one phase conductor of the electric circuit 6. Winding 9 may be connected in series with the associated phase conductor, or may be connected therewith through a current transformer, as is well known. The relay further comprises a core structure 10 and an armature 11. Armature 11 is of cylindrical form and is provided with a central opening 12 into one end of which a nut 13 is screwed. The armature is disposed adjacent core structure 10 to form therewith a magnetic circuit having a given air gap.

A core 14 extending through the central portion of armature 11 is threaded therein, and another core 15 is threaded in core 14. Core 15 is arranged within armature 11 and core 14 but extends beyond core 14.

The armature 11, nut 13, core 14 and core 15 are provided with aligned openings loosely receiving a rod 16 for actuating the circuit breaker switch arm 18. The rod 16 is provided with a flange portion 19 enclosed within armature 11 and having a sliding fit therewith. The lower end of the rod 16 is threaded into a nut 20 which is, in turn, suitably secured to one of a pair of suction disks. Nut 20 may be pinned to rod 16 to lock it in place, if so desired. A resilient means such as a spring 21 is arranged within armature 11 about rod 16 for opposing movement of armature 11 relative to rod 16. Spring 21 is mounted between flange 19 and a nut 22. Nut 22 is threaded into armature 11 and may be used for adjusting the tension of spring 21 without changing the relative position of armature 11 and core structure 10, thereby retaining the size of the original air gap. Nut 22, further, may be used to lock in position core 14, and a nut 23, as illustrated, will provide a definite arrangement between cores 14 and 15.

Another resilient means such as a spring 23 is arranged within armature 11 about rod 16 for opposing movement of armature 11 relative to rod 16. Spring 23 is arranged between flange 19 on rod 16 and a flange 24 mounted on core 14.

A rigid cylinder 27 surrounds the lower end of armature 11 and is suitably secured to core structure 10 and acts as a guiding means or bearing for the armature. Flange 19 of rod 16 acts as a guiding means for the upper end of armature 11, and a rigid cylinder 28 suitably secured to core structure 10 acts as a guiding means or bearing for the upper portion of rod 16 and also a stop for armature 11.

The suction disks are arranged in an oil bath with the upper disk 29 secured to rod 16 and the lower disk 30 secured to the bottom of a container 31 which houses the oil.

Circuit breaker 7 as illustrated in the drawing comprises stationary arcing contacts 32 and movable arcing contacts 33. The movable arcing contacts 33 are connected to a rod 34 which is actuated to circuit open position by a toggle mechanism 35.

The toggle mechanism 35 comprises a link 36 which is pivotally mounted at 37 and a link 38 which is pivotally mounted at a point 39 on rod 34. A spring 42 biases toggle mechanism 35 to circuit open position. Link 36 carries a lug 43 which is engaged by a catch 44. Catch 44 is mounted on one end of pivotally mounted lever arm 48 and is held in its operative position against a stop 45 by means of a spring 46. Lever arm 48 is actuated by rod 16 when the latter is

actuated to switch opening position by armature 11.

Fig. 2 is an enlarged diagrammatic view of a modification of the armature and controlling structure therefor, illustrated in Fig. 1. By adding a resilient means such as spring 47, acting between a flange 48 which forms a part of core 15 and flange 19, the operation of relay 8 may be varied to obtain a series of different time delay characteristics.

In Fig. 3 curve ABC illustrates a time current curve of the usual prior art current responsive relay. The curve ABDE illustrates the time current curve of the electromagnetic relay illustrated in Fig. 1, and the curve ABFG illustrates a time current curve of a relay of the type illustrated in Fig. 1 but incorporating the armature and controlling structure shown in Fig. 2. These curves are plotted with current as abscissas and time as ordinates. All of the curves are plotted on the basis of the relay being set for tripping only on values of current above 100% load. Fig. 3 illustrates diagrammatically the manner in which the relay incorporating the armatures illustrated in Figs. 1 and 2 may operate and is not intended to set any limits within which this invention must be restricted.

In operation, the circuit breaker 7 being closed as indicated in Fig. 1, current flows through the arcing contacts 32, 33 and the magnetizing winding 9. For all line currents below a certain value the parts of the relay remain in the position indicated. Upon the occurrence of an overload line current through magnetizing winding 9 below a predetermined value, the upward attraction of armature 11 is insufficient to compress springs 21, 23. However, the springs transmit the thrust exerted by the armature to rod 16. After a predetermined delay the disks separate and armature 11, springs 21, 23 and rod 16 move as a unit and actuate arm 18 to trip the circuit breaker 7.

Operation of the relay illustrated in Fig. 1 for overload currents below such predetermined value may be illustrated by curve AB in Fig. 3. This type of inverse time delay is characteristic of the prior art relay structures wherein the time delay is inversely proportional to the current flowing through the magnetizing winding for the full overload current range of the relay.

In order to permit the relay to operate faster for overload currents above a predetermined value the relay illustrated in Fig. 1 is provided with an armature which, when the current reaches the predetermined value, moves relative to the switch actuating rod 16 from a first position to a second position whereat the springs 21 and 23 are gradually compressed a predetermined distance depending on the current intensity. In the second position of armature 11, the air gap between the armature and the upper part of core structure is smaller.

The inverse time relation for a given relay setting for currents above the predetermined overload value is represented by curve BD. Therefore, the relay illustrated in Fig. 1 operates for all overload currents below a predetermined value on the curve AB and for all overload currents above the predetermined value on the curve BD.

By providing relay 8 with threaded cores 14 and 15 the tensions of springs 21 and 23 may be changed without changing the relative position of armature 11 with respect to core structure 10. By varying the tensions of springs 21 and 23, the inverse time relationship of the relay in the me-

dium current range is changed, and the point of changeover from one relationship to the other has been varied. When the tensions of springs 21 and 23 have been reduced by varying the relative positions of core 14 and nut 22 with reference to armature 11 the position of changeover from curve ABC to curve ABD, namely point B, will have been moved higher up on the curve ABC, i. e., to a higher time lower current position. Similarly, by increasing the tensions of springs 21 and 23 the position of point B of curve ABD may be moved to a lower position on the curve ABC, i. e., to a higher current lower time position. When the line current reaches or exceeds a second predetermined value, armature 11 moves into engagement with stop 23. In that position of armature 11, springs 21, 23 transmit to rod 16 a force which is independent of the value of the line current. In the high current range therefore rod 16 actuates arm 18 in a constant time regardless of the value of the line current. The operation of the relay in that range is accordingly represented by a horizontal line DE. This type of operation is desired when the line current exceeds the interrupting capacity of the circuit breaker and therefore should be interrupted by a faster back up circuit breaker of higher rating.

Curve ABFG is the time current curve of relay 8 when the relay incorporates the armature and controlling structure illustrated in Fig. 2. By providing spring 47 between flange 48 and flange 19 the armature 11 must operate during part of its movement against the combined actions of springs 21, 23 and 47. Spring 47 fits loosely into the armature assembly and is compressed only after armature 11 has moved a predetermined distance in switch actuating direction. Until spring 47 is compressed the relay operates as above set forth and as represented by curve ABD. However, when the relay reaches an operating point such as point F on curve ABD, the upward movement of armature 11 is arrested by spring 47. The energy absorbed by spring 47 in compressing under the upward movement of armature 11 is stored by spring 47 to be applied toward breaking the suction of disks 29 and 30 and toward accelerating rod 16. The operation of the relay in that range is represented by curve FG.

By changing the position of core 15 relative to armature 11 the distance that armature 11 may move before compressing spring 47 may be varied. When the distance of travel of armature 11 before compressing has increased over that illustrated in the drawing, the point F on curve ABFG will be moved lower down on the curve, i. e., to a lower time high current relationship. By decreasing the distance of travel of armature 11 before it starts to compress spring 47 the position of point F will be moved to a lower current higher time relationship.

The position of point B on curve ABFG may also be varied in a manner similar to point B on curve ABD by varying the initial tension on springs 21 and 23. Thus, a variety of time current relationships may be obtained from the same relay by simply varying the tension on the springs without varying the relative positions of armature and core structure.

Although but two embodiments of the present invention have been illustrated and described, it will be apparent to those skilled in the art that various changes and modifications may be made therein without departing from the spirit of the

invention or from the scope of the appended claims.

It is claimed and desired to secure by Letters Patent:

- 5 1. A time delay relay comprising a core structure, an armature disposed adjacent said core structure to form therewith a magnetic circuit having a given air gap, a magnetizing winding for producing a magnetic flux in said magnetic circuit, an operating rod having a flange arranged to be actuated by said armature, means for retarding the movement of said rod into actuated position in a time varying inversely of the value of the current traversing said winding, said armature comprising a cylinder and a nut, said cylinder enclosing said flange and said nut, resilient means acting between said flange and said nut for opposing movement of said armature relative to said rod, and means for varying the position of said nut relative to said cylinder for varying the tension of said resilient means without changing the length of said air gap.
- 10 2. A time delay relay comprising a core structure, an armature disposed adjacent said core structure to form therewith a magnetic circuit having a given air gap, a magnetizing winding for producing a magnetic flux in said magnetic circuit, an operating rod having a flange arranged to be actuated by said armature, means for retarding the movement of said rod into actuated position in a time varying inversely of the value of the current traversing said winding, said armature comprising a cylinder and a nut threaded within said cylinder, said cylinder enclosing said flange, a core threaded in said cylinder for movement therewith in an adjustable position, a first resilient means acting between said flange and said core for opposing movement of said armature relative to said rod, and a second resilient means acting between said flange and said nut for opposing movement of said armature relative to said rod, adjustment of the positions of said core and said nut relative to said cylinder varying the tensions of said first and second resilient means, respectively, independently of each other and without changing the length of said air gap.
- 15 3. A time delay relay comprising a core structure, an armature disposed adjacent said core structure to form therewith a magnetic circuit having a given air gap, a magnetizing winding for producing a magnetic flux in said magnetic circuit, an operating rod to be actuated by said armature, means for retarding the movement of said rod into actuated position in a time varying inversely of the value of the current traversing said winding, resilient means acting between said armature and said rod for opposing movement of said armature relative to said rod from a first position to a second position, and a second resilient means acting between said armature and said rod for opposing movement of said armature relative to said rod from said second position to a third position depending on the value of said current, said armature moving relative to said rod from said first position to said second position when the current traversing said winding reaches a predetermined value and from said second position to said third position when said current exceeds said predetermined value, said movement of said armature relative to said rod varying the inverse time relation between rod actuation and the value of said current.
- 20 4. A time delay relay comprising a core structure, an armature disposed adjacent said core

structure to form therewith a magnetic circuit having a given air gap, a magnetizing winding for producing a magnetic flux in said magnetic circuit, an operating rod having a flange arranged to be actuated by said armature, means for retarding the movement of said rod into actuated position in a time varying inversely of the value of the current traversing said winding, said armature comprising a cylinder and a nut threaded within said cylinder, said cylinder enclosing said flange, a first core threaded within said cylinder for movement therewith in an adjustable position, a second core threaded within said first core for movement therewith in an adjustable position, a first resilient means acting between said flange and said first core for opposing movement of said armature relative to said rod, a second resilient means acting between said flange and said nut for opposing movement of said armature relative to said rod, and a third resilient means arranged between said second core and said flange for opposing movement of said armature relative to said rod only after said armature has traveled a predetermined distance, said armature moving said predetermined distance relative to said rod from a first position to a second position when the current traversing said winding reaches a predetermined value and from said second position to a third position depending on the value of said current when said current exceeds said predetermined value, said movement of said armature relative to said rod varying the inverse time relation between rod actuation and the value of said current.

5. A time delay relay comprising a core structure, an armature disposed adjacent said core structure to form therewith a magnetic circuit

having a given air gap, a magnetizing winding for producing a magnetic flux in said magnetic circuit, an operating rod having a flange arranged to be actuated by said armature, means for retarding the movement of said rod into actuated position in a time varying inversely of the value of the current traversing said winding, a first resilient means acting between said armature and said rod for opposing movement of said armature relative to said rod from a first position to a second position, said armature moving relative to said rod from said first position to said second position when the current traversing said winding reaches a predetermined value, said movement of said armature relative to said rod varying the inverse time relation between rod actuation and the value of said current, and a second resilient means acting between said armature and said rod for opposing movement of said armature relative to said rod and becoming operative at a point intermediate said first and second position thereby varying the inverse time relation between rod actuation and the value of said current.
